UNITED STATES PATENT OFFICE.

WILLIAM H. McBARRON, OF ORANGE, NEW JERSEY, ASSIGNOR TO KLAXON COMPANY,
A CORPORATION OF DELAWARE.

DIAPHRAGM FOR MECHANICAL HORNS.

Application filed May 3, 1922. Serial No. 558,150.

To all whom it may concern:

Be it known that I, WILLIAM H. McBARRON, a citizen of the United States, and resident of Orange, in the county of Essex and State of New Jersey, have invented certain new and useful Improvements in Diaphragms for Mechanical Horns, of which the following is a specification.

My present invention is particularly designed for use in connection with horns of the type in which there is a rotary cam mounted directly on the armature shaft of an electric motor, the projections or teeth on the cam being arranged to contact with a wear piece on a steel diaphragm of suitable thinness and elasticity.

While capable of use in connection with other horns, it was primarily devised for use in the type wherein the armature shaft is perpendicular with the diaphragm at the center thereof, as for instance in Fig. 2 of Hutchison Patent No. 1,145,839, and also in the application of Duncan A. McConnel, Serial No. 558,108, filed May 3, 1922.

Having the armature shaft concentric with the diaphragm naturally locates the teeth of the cam at a distance from the diaphragm, yet for various reasons it is desirable to have the wear piece riveted at the center of the diaphragm. As it is not desirable to limit the diameter of the cam nor to enlarge the area of the wear piece to the extent indicated in Fig. 2 of the above-mentioned patent, it has been proposed to use centrally riveted clamping elements of suitably small clamping area and to provide it with a cam contact element located on a lateral projection which overhangs the diaphragm. In such an arrangement, the cam push has a noticeable tilting resultant because applied on the overhanging contact piece which acts as a lever. While this action tends to fatigue the metal and crack the diaphragm, I have discovered that for diaphragms which are sufficiently flexible, and with the structure herein described, the overhanging construction can be made durable enough to compare very favorably with diaphragms of the type in which the cam thrusts are delivered directly downward on the center of the wear piece.

The construction whereby the above results may be accomplished may be more fully understood from the following description

in connection with accompanying drawings, in which

Fig. 1 is a face view of the diaphragm and wear piece embodying my invention.

Fig. 2 is a section on the line 2—2, Fig. 1.

Fig. 3 is a section on the line 3—3, Fig. 1, showing the wear piece in elevation.

In these drawings, the diaphragm 1 is of thin, fine quality, spring steel, usually not less than four inches in diameter, and preferably between five and six inches in diameter, by say .02 to .025 inch in thickness, although it will be understood that certain features of the invention are of importance, independently of the dimensions.

The cam engaging member is preferably a drop forging which has been case hardened. As shown in the drawings, it comprises the clamping member 2 which is circular, the integral shank 4 which is preferably square, and the contact member 3 which is an eccentric projection formed so as to have an inclined contact surface 3^a leading up to a ridge 3^b, which extends substantially radial to the axis of the clamping member 2. This brings the said ridge opposite and parallel to the radially disposed tips of the cam projections on the rotary cam (not shown). Besides being eccentric this projection is thrust out of the plane of the clamping member 2 to produce the desired overhang with respect to the diaphragm. Preferably a strengthening rib 3^c is formed on the free rear edge of the projection in the drop forging operation.

The integral shank 4 is square and is riveted through a square aperture 6 in the center of the diaphragm 1, through a cushion washer 7 which is preferably made of the same spring steel as the diaphragm and through a front washer 8 which is heavy enough to maintain its shape and firmly clamp the diaphragm when the shank 4 is riveted therethrough as shown at 9. When made by forging or casting or other plastic method, the formation of a fillet 5 at the base of the shank 4 is practically unavoidable. At the same time it is highly desirable that the square shank 4 fit the squared hole 6 with great accuracy. Hence I prefer to employ the above-described spring steel washer 7 and to make its internal diameter larger than the shank 4 by an amount equal to or slightly greater than the base diameter of said

curved fillet 5. This permits the square hole in the diaphragm to fit the square shank accurately, and at the same time spaces the fillet away from the diaphragm so that the fillet cannot act as an expanding wedge to split the diaphragm. The steel washer 7 also tends to prevent cutting of the diaphragm under the tilting action which necessarily results from the overhanging position of the contact piece.

A further feature of my invention consists in having the overhanging contact piece extend in the general direction of the grain of the spring steel of the diaphragm, so that whatever tendency there may be to local cutting, fatigue or fracture of the metal of the diaphragm by the tilting will take effect transversely of the grain instead of parallel therewith. The direction of this grain is indicated in a general way by the parallel broken lines on Fig. 1. An index hole 10 may be punched in the edge of the diaphragm where it can do no harm, either structurally, mechanically or acoustically, yet will serve the useful purpose of indicating the direction in which the contact piece should project. The sides of the square hole in the diaphragm are so related to the grain of the metal, and the square sides of shank 4 are so related to ridge projection 3^b that one of the four possible positions for the shank in the hole must be the right one, and index hole 10 indicates which one of these four positions should be selected without necessity for the workman to inspect the direction of the grain at the time he assembles the parts.

In drop forging to form the wear piece the thrust is delivered directly downward on the head parallel with the axis of the shank so that the above-described fillet 5 is the only important imperfection found in the clamping surface or shank.

The radial overhanging length of the contact member 3 is about one-half the diameter of the clamping head 2 and the diameter of the spacing washer 7 is at least equal to and preferably very slightly greater than the diameter of said head. Consequently leverage of the overhang with respect to the clamp cannot be greater than 1 to 2, even for cam thrust applied at the point most remote from the center, and as the follow-up or thrust part of the cam impulse naturally tends to be near the base of the projection, the leverage of much of the thrust is very small and may be not greater than 1 to 5 or 1 to 8. Employment of the rib 3^a

permits desirable decrease of weight and inertia of the overhang element 3.

The diaphragm is cushioned from contact with the metal clamping members by elastic washers preferably of cork composition. It will be understood that the overhanging construction for the wear piece naturally cushions the impact of the cam, but, at the same time, it increases the tilting and reverse bending effects. I find, however, that where the motor power is suitably decreased, the strains are insufficient to produce destructive effects on the diaphragm. The overhanging position and resulting leverage of the wear piece makes it possible for a much weaker motor to start without danger of sticking on the first contact.

I claim:

1. A diaphragm of thin spring steel and riveted thereto a wear piece comprising diaphragm clamping elements and an overhanging contact member projecting laterally therefrom in the direction of the grain of the steel.

2. A diaphragm of thin spring steel and riveted thereto a wear piece comprising a drop forging having an integral shank, having at least one side flat and fitting a similarly shaped hole on the diaphragm, the disposition of the flat side of the shank and of the hole in the diaphragm being respectively such that the shank may be fitted into the hole with the overhang contact member parallel with the grain of the diaphragm.

3. A diaphragm of thin spring steel and riveted thereto a wear piece comprising a head portion having an integral shank riveted through the diaphragm and through a washer on the rear side thereof, the shank and head element being formed with a fillet at the base of the shank, in combination with a spacing washer between the head and the diaphragm, having a thickness at least as great as the height of the fillet and an internal diameter at least as great as the base diameter of the fillet.

4. A spring steel diaphragm and, riveted thereto, a wear piece comprising a clamping head, a malleable shank and an overhanging contact projection drop forged as an integral unit and said contact projection being case hardened.

Signed at Bloomfield, N. J. in the county of Essex and State of New Jersey this 11th day of April A. D. 1922.

WILLIAM H. MCBARRON.
